UNITED STATES PATENT OFFICE.

BENJAMIN F. TILLEY, OF LOUDONVILLE, OHIO.

HITCHING-POST.

SPECIFICATION forming part of Letters Patent No. 652,338, dated June 26, 1900.

Application filed December 4, 1897. Serial No. 660,737. (No model.)

To all whom it may concern:

Be it known that I, BENJAMIN F. TILLEY, a citizen of the United States, residing at Loudonville, in the county of Ashland and State 5 of Ohio, have invented certain new and useful Improvements in Hitching-Posts; and I do hereby declare the following to be a full, clear, and exact description of the invention, such as will enable others skilled in the art to

10 which it appertains to make and use the same.

This invention relates to improvements in hitching-posts, the object being to provide a hitching-post inclosed within a suitable casing and designed to be folded below the surface 15 of the ground when not in use and to be elevated and firmly locked in a vertical position when brought to the surface.

To this end the invention consists in providing a casing of simple and durable construction especially adapted to be embedded 20 in the ground and provided with a hinged lid or cover, a movable or folding post being mounted within the casing in a manner to permit its being folded entirely therein or to 25 be elevated and locked in operative position, as hereinafter described and claimed.

Referring to the drawings, Figure 1 represents a perspective view of the post embodying my invention in its extended or operative 30 position. Fig. 2 represents a central vertical section through the same when in its closed or inoperative position. Fig. 3 represents an enlarged detail perspective view of the post and its supporting-brace. Fig. 4 is a perspective view of a modified form of my invention, 35 showing the post elevated. Fig. 5 is a central longitudinal section through the subject-matter of Fig. 4, the post being shown depressed within the casing; and Fig. 6 is a perspective view of this form of the invention, 40 the parts being in the position shown in Fig. 5.

Referring to the preferred form of my invention illustrated in the first three figures of the drawings, 1 represents the hollow casing 45 of my improved device, 2 the post proper, and 3 the brace. Said casing 1 may be of any desired construction and material adapted to accommodate the post 2 and brace 3 when the two latter are doubled down into 50 the same. Said casing 1 is provided at one end with an extension 4, having an inclined brace 5, which latter forms one of the ends of

said casing and also assists in holding said extended base portion 4 firmly in position. This latter base portion is intended to prevent any upward movement of the casing 1 after the same has been buried beneath the surface-line of the pavement or road in which the post is to be applied. The interior of said casing 1 is provided in proximity to its 55 base portion with side ledges or supports 6 6, upon which the hinged brace 3 is adapted to rest when the post and brace are doubled down into the casing. Said ledges 6 6 terminate a short distance in front of the pivot-point of the post 2, so as to provide space for the enlarged end 7 of said post, which is pivotally mounted between the side walls of the casing 1 by a pivot-pin 8. The upper or reduced portion 9 of the post proper is adapted 70 to rest upon the top of the brace 3 when the post and brace are doubled down into the casing. The upper end of the brace 3 is hinged to the post 2, as at 10, so that when said post is brought to a vertical position the 75 brace will lie flat against the inclined wall 11, which connects the upper reduced portion of the post and the lower enlarged portion. The lower end of said brace 3 is held firmly in place when the post is in a vertical position by a stop 80 12, located between the supporting-ledges 6 6 and secured to the bottom of the casing 1. The pivot-point 8 of the post proper is located at some distance from its lower end, so that when it is desired to raise the post out of the 85 casing a slight kick or pressure upon said post forward of said pivot-point will raise the opposite end of the post sufficiently to be grasped to raise it. When the post is in its raised position and it is desired to lower the 90 same, the lower end of the brace 3 is first disengaged from the projection 12 by a slight upward movement and said brace and post then doubled down into the casing out of the way. When in this position, the side of the 95 post lies flush with the top of the side walls of the casing 1, so that the same will offer no obstruction to the wheels of vehicles passing over the same. The upper end of said post 2 is provided with any suitable hitching ring 100 or hook, to which the reins or other portions of the harness may be secured. I also contemplate providing the casing 1 with a removable cover 13 for preventing the entrance

of snow or ice during the winter months, but this is not essential to the operation of my invention.

- In the last three figures of the drawings I have illustrated a form of the invention especially designed for use in cold climates, where the snow and ice would be apt to accumulate in the casing with the post in the elevated position, as it will be observed that 5 the casing is necessarily left open when the post heretofore described is elevated. The distinguishing feature of this form or construction is a sectional cover, one section of which is designed to be closed over the casing to protect the latter and at the same time constitute locking means for retaining a hitching-post rigidly in a vertical position. The use of the cover for this purpose obviates the necessity for the use of the brace 5.
- 10 Referring to the numerals on the last three figures of the drawings, 14 indicates a casing composed, essentially, of side pieces 15 and 16, end pieces 17 and 18, and a sectional cover composed of two independently-hinged sections 19 and 20, provided at their contiguous edges with an inclined or rabbeted lapping joint, as illustrated, for the purpose of permitting them to lie in close contact and prevent the admission of foreign matter when turned 15 down to a horizontal position. The section 20 of the cover when folded inward, as shown in Fig. 4, acts as a hinged brace to hold the hitching-post 22 upright. The side pieces are extended upwardly at one end to a point flush 20 with the upper surface of the cover when the latter is closed, in order that the top of the entire casing, with the exception of the extreme ends, which are inclined, as shown, will lie substantially flush with the ground, 25 the inclination or end of the casing serving 30 to cause a layer of earth to project a sufficient distance upon the top of the casing to insure its position and to prevent it becoming dislodged under a strain exerted upon the post.
- 35 One of the end pieces may be extended somewhat in order to form an anchor or fin 21; but this is immaterial, and is only illustrated as showing one means of insuring the permanency of the device.
- 40 22 indicates the hitching-post proper, pivoted at or adjacent to its lower extremity, as by a pintle 23, passing transversely through the casing immediately in front of the end piece 18, the relation of the parts being such that 45 when the post is elevated the adjacent end piece will act as a stop to limit the movement of the post in one direction. The cover, which has been turned back to permit the elevation 50 of the post, is now turned down in the direction of the casing until the section 19 impinges against the side of the same and the section 55 20 rests flat upon the top of the casing and

constitutes a stop, brace, or locking mechanism, preventing movement of the post in a direction opposite the end piece against which it impinges. It will now be seen that the post is securely held between the contiguous faces of the cover-section 20 and the adjacent end section and that said cover-section will completely inclose the cover-section to inclose the 65 casing and protect the same from the disintegrating action of an accumulation of water, snow, or ice. A stop-pin 23' may be provided within the casing to retain the other end of the post when it is folded therein, and in the 70 latter position both sections of the cover are folded down and the entire device lies substantially flush with the ground and presents no obstacle to the passage of vehicles, &c.

It may be remarked in conclusion that the 80 casing and post may be made of any suitable material; but at the present time metal is considered favorable by reason of its durability.

While I have illustrated and described what appear to be the preferable forms of my invention, I do not desire to limit myself to the structural details set out, but reserve the right to make such changes as may come within the scope of the protection prayed.

Having thus described the invention, what 90 is claimed as new is—

1. A hitching-post comprising a casing, a hitching-post proper pivotally mounted and housed therein, and a hinged brace adapted to engage and hold the post in an upright position, substantially as described.

2. In a hitching-post, the combination with a suitable casing, of a post pivotally mounted therein in such manner as to adapt it to be folded into the casing, and a divided hinged 100 cover entirely closing said casing when the two parts of the cover are folded down upon it, one part thereof being adapted to lock the post in its elevated position, substantially as described.

3. The combination with a suitable casing adapted to be embedded in the ground, of a hitching-post pivotally mounted therein at one end in such manner as to adapt it to be folded into the casing, and a divided hinged 110 cover for said casing, one part thereof being adapted to lock the post in its elevated position, the adjacent ends of the parts of the divided cover being provided with a lap-joint and the two parts of the divided cover when 115 folded down completely closing the casing, substantially as described.

In testimony whereof I affix my signature in presence of two witnesses.

BENJAMIN F. TILLEY.
